DESIGN FOR A REFRIGERATOR

Richard B. Janes, Greenville, Mich., assignor to Gibson Electric Refrigerator Corporation, Greenville, Mich., a corporation of Michigan

Application May 19, 1942, Serial No. 106,951

Term of patent 7 years

To all whom it may concern:

Be it known that I, Richard B. Janes, a citizen of the United States, residing at Greenville, in the county of Montcalm and State of Michigan,
have invented a new, original, and ornamental Design for a Refrigerator, of which the following is a specification, reference being had to the accompanying drawing, forming a part thereof.

In the drawing:

The figure is a front perspective view of a refrigerator, with the outer door open, showing my design.

The characteristic features of the design reside
in the portions shown in full lines.

I claim:

The ornamental design for a refrigerator, substantially as shown and described.

RICHARD B. JANES.
